UNITED STATES PATENT OFFICE.

STACY B. HASELTINE, OF CHICAGO, ILLINOIS, ASSIGNOR TO W. H. MINER, INC., OF CHICAGO, ILLINOIS, A CORPORATION OF DELAWARE.

SHOCK-ABSORBING MECHANISM.

Application filed February 28, 1927. Serial No. 171,417.

This invention relates to improvements in shock absorbing mechanisms.

One object of the invention is to provide a tandem spring shock absorbing mechanism 5 of simple design comprising a minimum number of parts and providing an exceedingly rugged construction, presenting a heavy column load sustaining element limiting the compression of the mechanism.

Another object of the invention is to provide a tandem spring shock absorbing mechanism, including front and rear main follower casings for transmitting the actuating pressure to rear and front intermediate followers to effect compression in tandem of 15 spring resistance elements, wherein the inner ends of the main follower casings are adapted to abut throughout, to present a solid column of great strength to limit movement of the parts of the mechanism when the same is fully compressed and transmit the actuating force to the draft sills, preventing the spring resistance elements from being unduly compressed.

A more specific object of the invention is to provide a spring shock absorbing mechanism of the character indicated, including duplicate front and rear main follower casings; duplicate intermediate follower members; and tandem arranged spring resistance elements, wherein the intermediate follower members are telescoped within the follower casings and the front and rear intermediate followers co-operate with abutments on the 30 rear and front main follower casings respectively to compress the spring resistance means in tandem.

Other objects of the invention will more fully and clearly appear from the description and claims hereinafter following.

In the drawings, forming a part of this specification, Figure 1 is a horizontal longitudinal sectional view of a portion of a railway draft rigging, illustrating my improvements in connection therewith. Figure 2 is a vertical transverse sectional view corresponding substantially to the line 2—2 of Figure 1. Figure 3 is a diagonal transverse sectional view corresponding substantially to the line 3—3 of Figure 2. And Figure 4 is a front end elevational view of one of the intermediate followers employed in connection with my improved shock absorbing mechanism.

In said drawings, 10—10 indicate channel-

shaped center or draft sills of a railway car underframe, to the inner sides of which are secured front stop lugs 11—11 and rear stop lugs 12—12. The inner end of the drawbar is designated by 13, to which is operatively 60 connected a yoke 14 of well known form. The shock absorbing mechanism proper is disposed within the yoke, and the yoke and the parts therewithin are supported by a detachable saddle plate 15 fixed to the draft 65 sills.

My improved shock absorbing mechanism comprises, broadly: Front and rear main follower casings A—A; front and rear intermediate followers B—B; and tandem arranged 70 spring resistance elements C—C.

The front and rear main follower casings A are of similar design, each being in the form of a rectangular hollow-box-like member having longitudinally disposed vertical side walls 16—16, longitudinally disposed horizontal top and bottom walls 17—17, and a transverse outer end wall 18. The end wall 18 of the casing is laterally extended beyond the side walls thereof as clearly shown in 80 Figures 1 and 2, thereby presenting a relatively large bearing face adapted to co-operate with the corresponding stop lugs. The casing A and the end wall 18 thereof are reinforced by horizontal ribs 19. The end 85 walls 18 of the casings A co-operate with the stop lugs 11 and 12, respectively, in the manner of the usual front and rear main followers. At the inner ends thereof, the casings are provided on the interiors thereof with inwardly extending integral stop lugs 20 at 90 two diagonally opposite corners thereof. The stop lugs 20 of the front casing A are disposed in alignment with those diagonal corners of the rear follower casing A which do 95 not carry the stop lugs.

The intermediate followers B are of similar design, each comprising a body portion 21 having longitudinally projecting arms 22 at one side thereof. The arms 22 are shouldered, as indicated at 23 and the outer ends of the same are adapted to bear on the stop lugs 20 of one of the casings A. Each intermediate follower B is also cut away at two oppositely diagonal sides as indicated at 24 to provide clearance for the arms 22 of the other intermediate follower. Each intermediate follower B is also provided with continuous flanges 25—25 on diagonally opposite sides thereof adapted to normally bear 105 110

on the flanges 25 and the stop shoulders 23 of the arms of the other intermediate follower B. The two intermediate followers B are interlaced so that one of the same forms a front intermediate follower and the other a rear intermediate follower. The front intermediate follower B has the arms 22 thereof extending rearwardly and bearing on the stop lugs 20 of the rear casing A, and the rear intermediate follower B has the arms 22 thereof extending forwardly and bearing on the stop lugs 20 of the front follower casing A. It will be evident that the two intermediate followers B are thus mounted for movement in unison respectively with the front and rear casings A. Each of the intermediate followers B has a flat outer end face adapted to bear on the inner end of one of the members of the tandem arranged springs C. The tandem arranged springs C comprise front and rear units, each including a relatively light inner coil and a heavier outer coil. The front spring unit C is interposed between the end wall 18 of the front follower casing A and the front intermediate spring follower B and the rear spring unit is interposed between the rear intermediate follower B and the rear end wall 18 of the rear main follower casing A. Both of the spring units C are housed entirely within the casings A.

As clearly shown in Figure 1, the inner ends of the casings A are spaced apart a distance equal to the permissible compression stroke of the mechanism so that when the gear is fully compressed, the inner ends of the casings will abut along the edges of the top, bottom and side walls, thereby presenting in effect a continuous column element adapted to transmit the actuating force directly to the stop lugs on the draft sills and prevent the spring resistance elements C from being unduly compressed.

The operation of my improved shock absorbing mechanism, assuming a compression stroke, is as follows: The front and rear casings A will be moved relatively toward each other, thereby moving the rear intermediate follower B and the end wall 18 of the rear casing A toward each other and moving the front intermediate follower and the front end wall 18 of the front casing A toward each other, compressing both members of the spring resistance means in tandem. The compression stroke will continue either until the actuating force is reduced, or movement of the casings A relatively to each other is limited as hereinbefore described by their inner ends coming into abutment. When the actuating pressure is reduced during release, the spring resistance elements C will effect restoration of all of the parts of the mechanism to the normal position of the parts illustrated in Figure 1.

While I have herein shown and described

what I now consider the preferred manner of carrying out the invention, the same is merely illustrative, and I contemplate all changes and modifications that come within the scope of the claims appended hereto.

I claim:

1. In a spring shock absorbing mechanism, the combination with front and rear main follower casings having outer end walls functioning as front and rear main followers and open inner ends; of front and rear intermediate followers telescoped within and completely encircled by said casings, said rear and front intermediate followers being movable with the front main follower casing and the rear main follower casing respectively; and tandem arranged spring resistance elements, one of the members of which is interposed between the end wall of the front follower casing and the front intermediate follower, and the other of which is interposed between the rear intermediate follower and the end wall of the rear main follower casing.

2. In a spring shock absorbing mechanism, the combination with front and rear main follower casings having front and rear main follower elements formed integral therewith, said casings being relatively movable toward and away from each other and adapted to have their movement limited by engagement with each other; of stop shoulders on the interiors of said casings; separate front and rear intermediate follower elements bearing respectively on the interior stop shoulders of said rear main and front main follower casings; and spring resistance means interposed respectively between said front main and front intermediate followers and between said rear main and rear intermediate followers.

3. In a tandem spring shock absorbing mechanism, the combination with front and rear casings relatively movable toward and away from each other; of front and rear spring resistance elements within said casings; and separate front and rear intermediate followers operatively associated with said rear and front casings respectively and bearing respectively on said front and rear springs, said intermediate followers being telescoped within and completely encircled by said casings.

4. In a tandem spring shock absorbing mechanism, the combination with front and rear casings relatively movable toward and away from each other; of front and rear intermediate followers, said front intermediate follower being telescoped within the front casing and having arms spanning the rear intermediate follower and bearing on the rear casing, said rear intermediate follower being telescoped within the rear casing and having arms spanning the front intermediate follower and bearing on the front casing; and front and rear spring resistance elements

within said front and rear casings and bearing respectively on said front and rear intermediate followers.

5. In a tandem shock absorbing mechanism, the combination with front and rear rectangular casings having stop shoulders at two diagonally opposite corners thereof; of front and rear intermediate followers, each having arms at two diagonal corners thereof and having the remaining diagonal corners cut away, the arms of each of said intermediate followers spanning the other intermediate follower at said cut away corners thereof, the arms of the front intermediate follower bearing on the stop shoulders of said rear casing and the arms of said rear intermediate follower bearing on the stop shoulders of the front casing; and front and rear resistance means within said front and rear casings and bearing on the front and rear intermediate followers respectively.

6. In a tandem shock absorbing mechanism, the combination with front and rear

follower casings having outer end walls and side walls and open at their inner opposed ends, the inner ends being adapted to directly engage around their entire peripheries at the end of a full compression stroke; of separate front and rear intermediate followers telescoped within the front and rear casings; means extending between the front intermediate follower to the interior of the rear follower casing for actuating the front intermediate follower in unison with the rear casing; means extending between the rear intermediate follower and the interior of the front casing for actuating the rear intermediate follower in unison with the front casing; and cushioning means interposed between each intermediate follower and the corresponding follower casing within which it is telescoped.

In witness that I claim the foregoing I have hereunto subscribed my name this 16th day of February, 1927.

STACY B. HASELTINE.
